(57) **CLAIM**

The ornamental design for a laminate stairnose molding, as shown and described.

DESCRIPTION

FIG. 1 is a top perspective view of the laminate stairnose molding;

FIG. 2 is a side perspective view of the laminate stairnose molding;

FIG. 3 is a bottom view of the laminate stairnose molding; and,

FIG. 4 is a side view of the laminate stairnose molding, the opposite end view being a mirror image thereof.

It should be understood that the laminate transition molding of the present drawings is an indeterminate length, which may be cut to a length as needed; the length shown in FIGS. 1-4 is for convenience of illustration.
